UNITED STATES PATENT OFFICE.

GUSTAV A. F. AHLBERG, OF PITTSBURGH, PENNSYLVANIA.

CARBURETER.

1,356,117.

Specification of Letters Patent. Patented Oct. 19, 1920.

Original application filed March 6, 1914, Serial No. 822,875. Divided and this application filed June 29, 1916. Serial No. 106,683.

To all whom it may concern:

Be it known that I, GUSTAV A. F. AHLBERG, a citizen of the United States, residing at Pittsburgh, in the county of Allegheny and State of Pennsylvania, have invented certain new and useful Improvements in Carbureters, of which the following is a description, reference being had to the accompanying drawings, forming a part of this specification, in which corresponding letters of reference in the different figures indicate like parts.

My invention relates to that class of carbureters adapted more especially for the use of kerosene and other heavy hydro-carbon oils, this being a division of my application filed March 6th, 1914, as Serial No. 822,875. The object of my invention is to provide novel and effective means for utilizing heat from the motor exhaust for heating carbureting and mixing chambers together with air and fuel admitted thereto so as to vaporize the heavy fuel in a simple, effective and economic manner. To these ends, my invention consists in the combination of elements hereinafter more particularly described and definitely pointed out in the claims.

In the drawings, Figure 1, is a plan view of my improved carbureter,

Fig. 2, is a longitudinal section thereof, taken upon the line II—II, Fig. 1, viewed in the direction of the arrow there shown,

Fig. 3, is a like section forming a part of Fig. 2, being a continuation at the left hand end thereof,

Fig. 4, is a section in plan taken upon the line IV—IV, Fig. 2.

Figs. 5, 6 and 7 are vertical sections taken upon the lines V—V, VI—VI and VII—VII respectively, Fig. 2, viewed in the direction indicated by the arrows there shown, and

Fig. 8, is a section in plan taken upon the line VIII—VIII, Fig. 2.

Referring to the drawings, 1, indicates that portion of a carbureter casing which is attached to the motor, the flange 2, thereon being provided for that purpose. To a flange 3, arranged at right angles to the flange 2, is bolted or otherwise rigidly secured a flange 4, which is integral with an elongated shell 5, the interior of which is cylindrical and is intended to form a carbureting chamber 6. A portion of said shell

5 is provided with a jacket 7 for the purpose hereinafter stated. A main heating case, generally designed by 9, is provided with a flange 10, Fig. 1 bolted to a flange 11, formed upon the part 7. The heating case 9 is provided with an opening in the top to which is detachably secured a tight cap 12, preferably protected by means of an asbestos shield 13. Within the shell 9 is a secondary shell 14, Fig. 2, between which and the outer shell is an annular space or chamber 15, for the purpose hereinafter stated. Tapped into an annular flange 16 is a tubular radiator member 17; open at the bottom but closed at the top, said member being provided with heat radiating projections 18 and constituting a secondary heating conduit. A short pipe 19, is connected by means of an elbow 20 with the pipe 17. The pipe 19 is adapted to connect with the motor exhaust so as to receive therein the heated products of combustion. Tapped into the bottom of the casing 9 is a plug 21, Fig. 2, having a conical end the apex of which coincides with the axis of the tube 17, the purpose of said plug being to regulate the size of the discharge opening from the bottom of said tube. The discharge from the tube 17 enters the annular space 15, which is in communication by means of a semi-annular passage 22, with an annular chamber 23, in the jacket 7. Said chamber in turn is in communication with an exhaust opening 24.

The heating space between the radiating member 17 and the inner wall 14 of the jacket 9, as well as the space within the casing 5 is in communication with the outer atmosphere through a passage 25, Figs. 2 and 4, the effective opening to which is controlled by means of a sliding gate 26, held in place by means of an adjusting screw 27.

A metal tube 28, which constitutes a primary heating conduit for the carbureting chamber 6, is inclosed within the tubular casing 5 and is arranged concentrically therewith. One end of said tube is in communication with the tube 17 through an elbow 29 formed in the latter, while the other is incased within a hollow plug 30, Figs. 1, 2 and 3, which is tapped into a flanged bore in the casing 1. Said plug is provided with lateral openings 31 to permit the exhaust from the tube 28 to escape into the atmosphere. A throttle valve 32, Fig. 2, is pivoted diametri-

cally in the pipe 19, said valve having an actuating arm 33 rigidly attached thereto. A link 34 serves to connect the end of the arm 33 to one arm of an elbow lever 35 pivoted at 5 36 to a boss 37 in the lower part of the pipe 17. A lever 38, is connected to a pin 39 upon the depending arm of the lever 35. The upper end of the lever 38 is pivoted at 40 to a bracket 41. A rod 42 is located within 10 the tube 28 and has one end pivotally connected at 43 to the lever arm 38, while the opposite end is centrally tapped, as shown at 44, Fig. 3, through the plug 30 and provided with a nut-lock 45. The device described constitutes a thermostat and is so 15 adjusted that when the carburetor is cold, the valve 32 will be fully open, but when heated the expansion of the rod 42, acting through the levers 38 and 35 and the link 34 and arm 33, will cause the valve to close more or less in proportion to the degree of heat developed from the motor exhaust.

The part 1 of the casing is enlarged in diameter in the direction of the shell 9, as 20 shown in Fig. 2, so as to form a valve-chamber leading to a mixing chamber 46, into which a portion 47, of the casing 5 is extended in the form of a nozzle as shown. A valve 48 having a hub 49, is slidably 25 mounted upon the tubular extension or nozzle 47, formed in the flange 4. Openings 51, Figs. 2, 5 and 7, are formed in the flange 4 to communicate with the atmosphere. A coiled spring 52 tends to hold the 30 valve 48 normally closed.

Extending through bores in the flange 4, are pins 53, Figs. 1, 2 and 7, which are rigidly attached to the valve 48. A lever 54 is pivoted to a bracket 55 upon the flange 4, said lever having bifurcated arms 56 arranged to engage the pins 53. The opposite end of said lever is in engagement with a spring 57, Fig. 2, which is interposed between it and an adjusting screw 58, tapped into a bracket 59 on said casing. The head 60 of said screw is bored out to form a cavity for the reception of the spring, while peripheral grooves 61 are formed in said head to receive a retaining spring 62 upon the end of the bracket 59. By means of the screw 58, the tension of the screw 57 may be adjusted to vary the resistance of the valve spring to any desired degree.

Formed upon the side of the main casing 55 is an oil reservoir 63, Figs. 1 and 5, having a removable cap 64 which is centrally bored as shown in Fig. 5, to receive and guide a vertical valve-stem 65, the upper end of which is covered and protected by a removable cap 66. Rigidly attached to said valve-stem is a hub member 67 having a peripheral groove 68 therein which is adapted to receive and engage the short arms of counterweight levers 69, pivoted to lugs 70 upon the cap. A loose float 71 is placed within

the reservoir and adapted to lift the counterweights as oil is permitted to enter the reservoir.

The lower end of the valve-rod 65 is tapered to form a valve and close the opening 72 in a valve-plug 73 having a central guiding bore in its top for guiding the valve-rod, and lateral openings 74 to permit the oil to enter the reservoir. A nipple 75 enables the reservoir to be connected to the supply tank from which a full feed may be received subject to the control of the valve. The features of said device are common and well known and I make no claim thereto.

An offset 76, Figs. 2 and 5, is formed in the reservoir casing directly beneath the main casing 5. A plug 77 is tapped through the bottom of said offset for the screw-threaded portion of a valve-stem 78 which is tapped therein. A plug 79 in axial alignment with the plug 77 is tapped into the main casing above said offset so as to extend into the carbureting chamber 6 of the main casing. Said plug is provided with an enlarged feed bore 80, a reduced bore 81 to form the valve seat and an enlarged bore 82 to form a discharge. The exterior middle portion of the valve plug is reduced in diameter as shown, to form 90 an annular chamber 83, from which oil may flow through lateral bores 84. The upper end of the valve plug 79 is passed through a bore in a ring 85, located in the carbureting chamber to form a restricted cross- 100 sectional area for the purpose of increasing the suction past the fuel inlet opening which is made flaring as shown at 86. A hand-wheel 87 is attached to the valve-stem, 105 said wheel having peripheral notches for engaging a spring-controlled stop 88 to enable the valve to be adjusted.

A horizontal bore 89, Figs. 2 and 6, is arranged to communicate with the annular chamber 83 and also with a lateral bore 90. 110 A hollow plug, generally designated by 91, Fig. 6, is tapped into the casing from beneath, the lower portion thereof forming a supplemental or emergency reservoir 92, while the upper portion 93 forms a nipple 115 or discharge nozzle having a central bore 94 and lateral bores 95, which latter are in communication with the passage 90. Bores 96 also lead to the reservoir 92 to enable oil 120 to enter the latter from the passage 90. Oil may be drawn from the reservoir by suction through a small tube 97.

Between the main casing 5 and the tube 28 is interposed a tube 98, arranged parallel to the tube 28 which is grooved as shown at 99 to fit the tube 98. The latter is open at both ends, one of which is bent downward as shown at 100 to receive the nozzle 93, while the other is bent upwardly as shown at 101 into a bore 102, Fig. 2, in commun- 130

cation with a small discharge port 103, slightly below but in close proximity to a throttle valve 104 mounted upon a journal 105 supported in bearings in the casing 1 to control the outlet therefrom which may be actuated in any well known way.

A screw plug 106, Figs. 2 and 8, is tapped into a bore 107 in communication with the bore 102 for the purpose of regulating the 10 quantity of fuel mixture which may be delivered to the port 103. The reservoir 92 which is provided with very thin walls, I prefer to heat electrically by the following described means: A generator, 108, Fig. 2, 15 has one of its terminals connected by a lead 108' with a coil 109 Fig. 6, surrounding the reservoir 92; the other terminal 110 of the coil being extended to form a heating coil 111, within the casing 5, which coil is 20 interposed between said casing and a thin copper tube 112. The opposite terminal of the coil 111 is carried by means of a lead 113 shown in Fig. 1 and diagrammatically indicated in Fig. 2, back to the generator, 25 the two coils being connected "in parallel." A switch 114 is interposed in the circuit. The emergency reservoir together with the preliminary heating means for starting the engine forms the subject matter of claims 30 in my pending application above referred to.

The operation is as follows:

In starting, the switch 114 is closed until the reservoir and carbureting chamber be- 35 come heated. The throttle-valve 104 is then opened just enough to expose the port 103 while still closing the main passage through the carbureting and mixing chambers. As a result of this adjustment, a strong suction 40 from the aspiration of the motor is induced through the port 103 and tube 98, thereby causing a suction through the primary jet 93 and openings 95, passages 90, 89, openings 84 and valve opening 80. Fuel is thus 45 drawn from the latter, discharged through the primary jet 93, where it is commingled with the air in the tube 98, and the combustible mixture is, in turn, delivered through the port 103 to the combustion chamber of 50 the motor. As soon as the motor starts the products of combustion are discharged from the exhaust, a portion thereof passing directly through the pipe 28 to the openings 31 and a portion through the pipe 17 and 55 jacket chambers 15 and 23 respectively, to the discharge 24, thereby serving to heat the entire casing. As soon as this is accomplished the switch 114 is opened as is also the throttle valve 104. Upon opening the latter 60 the suction through the port 103 ceases, being transferred to the main passageway which results in drawing air from without through the passage 25 and the annular heating chamber inclosed by the jacket 9, into con- 65 tact with the radiating surfaces 18, from

whence it passes through the annular space between the main casing and the heating pipe 28 past the throttle valve 104 to the motor.

The action of the fuel jets and of the valve 70 48 are fully described in my above named pending application and inasmuch as my claims herein relate to the main heating features, they need not be further referred to.

It is known that the degree of heat re- 75 quired to raise kerosene to a temperature which will cause it to give out the highest motive efficiency must be closely regulated and maintained. Should the heat in the reservoir be too low or too high, the excess in 80 either direction will cause an increase of fuel consumption and correspondingly lessen the accomplished work. It is therefore, es- 85 sential that the controlling factor should be automatic. The thermostat described in- 90 sures the desired conditions. The rod 42 is so adjusted that when the carbureter is cold, the throttle valve 32 will be fully open; but as the heat in the pipe 28 is increased, the rod will expand, thereby moving the inter- 95 posed levers, closing the throttle to the de- 95 sired degree and proportionately shutting off the supply of heat from both the pipe 28 and the chamber 23.

I have found in practice that by following 95 the operation described, a motor may be readily started with kerosene alone, and that the combustible mixture may be so perfectly blended and its uniformity so main- 100 tained as to insure maximum working effi- ciency, which necessarily implies the ab- sence of smoke and offensive odor.

Having thus described my invention, I claim:

1. A carbureter, comprising, in combina- 105 tion, a jacketed carbureting chamber, a primary heating conduit extending longitudinally through said carbureting chamber and communicating at one end with the exhaust port of an engine and at its other end with the atmosphere, a secondary heating con- 110 duct also in communication with said exhaust port, and a jacketed casing arranged to surround said secondary conduit in spaced rela- 115 tion thereto to form an air passage having an air inlet opening, said passage being in communication with said carbureting chamber whereby air may be heated before enter- 120 ing the latter, the space inclosed by the jacket of said casing being in communica- 125 tion with said secondary conduit and with the space inclosed by the carbureting chamber jacket, which latter communicates with the atmosphere.

2. A carbureter, comprising, in combina- 125 tion, a jacketed carbureting chamber, a primary heating conduit extending longitudinally through said carbureting chamber and communicating at one end with the exhaust port of an engine and at its other end with 130

the atmosphere, a secondary heating conduit also in communication with said exhaust port and diverging from said primary conduit at a point between said exhaust port 5 and said carbureting chamber, and a jacketed casing arranged to surround said secondary conduit in spaced relation thereto to form an air passage having an air inlet opening, said passage being in communication 10 with said carbureting chamber whereby air may be heated before entering the latter, the space inclosed by the jacket of said casing being in communication with said secondary conduit and with the space inclosed by the carbureting chamber jacket, which latter communicates with the atmosphere.

3. A carbureter, comprising, in combination, a jacketed carbureting chamber, a primary heating conduit extending longitudinally through said carbureting chamber and

communicating at one end with the exhaust port of an engine and at its other end with the atmosphere, a secondary heating conduit also in communication with said exhaust port and formed with peripheral heat radiating projections, and a jacketed casing arranged to surround said secondary conduit in spaced relation thereto to form an air passage having an air inlet opening, said passage being in communication with said carbureting chamber whereby air may be heated before entering the latter, the space inclosed by the jacket of said casing being in communication with said secondary conduit and with the space inclosed by the carbureting chamber jacket, which latter communicates with the atmosphere.

In testimony whereof, I have signed this specification, this 27th day of June, 1916.

GUSTAV A. F. AHLBERG.
